UNITED STATES PATENT OFFICE.

ROBERT M. KINNARD, OF KITTANNING, PENNSYLVANIA, ASSIGNOR OF ONE-THIRD TO JAMES Y. BOWSER AND JOHN S. FREDERICK, BOTH OF KITTANNING, PENNSYLVANIA.

BARREL-JACK.

1,158,235.

Specification of Letters Patent. Patented Oct. 26, 1915.

Application filed March 4, 1915. Serial No. 11,993.

To all whom it may concern:

Be it known that I, ROBERT M. KINNARD, a citizen of the United States, and resident of Kittanning, in the county of Armstrong and State of Pennsylvania, have invented 5 certain new and useful Improvements in Barrel-Jacks, of which the following is a specification.

The object of this invention is to provide 10 a stand or support of simple and improved construction for supporting an oil or other barrel in convenient position for dispensing its contents, the support being adjustable for varying the angle at which the barrel is 15 sustained.

A further object is to provide improved 20 means for securely uniting the support and barrel whereby the latter is held against displacement when the support is in upright position, and whereby the support is adapted 25 to cooperate with the barrel and facilitate movement thereof from position when resting on its side to full upright stand-supporting position.

It is further characteristic of the invention 30 that the adjustable support is embodied in a collapsible structure which is adapted to fold into relatively compact form when not in service.

In the accompanying drawings, Figure 1 35 illustrates in full lines the improved support applied to a barrel when resting on its side and in dotted lines indicates the manipulation of the supported barrel in up-ending the latter prior to tipping the barrel into the ultimate supported position illustrated in Fig. 2. Fig. 2 is an elevation of the support and barrel in full upright position. Fig. 3 40 is an end view with the parts in the position shown in Fig. 2, and Fig. 4 is a top plan of the support with the barrel removed.

Referring to the drawings, 2 designates 45 the upwardly divergent cradle-forming arms which embrace the lower half of the barrel when the latter is being supported as in Fig. 2, the arms being secured together beneath the barrel by the pivot-forming bolt or rivet 3, and from this point of union the arms 50 diverge downwardly to form the parallel legs 4 on which are mounted the caster rollers 5, the extremities of the arms being projected and pointed as indicated at 4'. The arrangement is preferably such that when the support is in use pivot 3 is located some-

what nearer end b' of barrel B than end b, 55 and arms 2 are curved or offset toward end b', while legs 4 are curved or offset in the opposite direction so that casters 5 are located well toward end b.

Bar 6 is disposed substantially at right 60 angles to the convergent portions of arms 2 and legs 4 and is secured between its ends on pivot bolt 3. One end of bar 6 extends toward barrel end b, as indicated at 7, and is formed with hook 7' to engage the chine at 65 said end. At the opposite side of the pivot, bar 6 extends toward barrel end b', being bifurcated to form a pair of downwardly converging legs 8 on which are mounted floor casters 9 located almost directly beneath barrel end b'. Crotch 10 at the intersection of legs 8 provides a hold for adjusting bar 11, the lower end of the latter being secured to cross-bar 11' connecting legs 4. Bar 11 is provided with a series of 70 stop-forming pins 12, one or another of which is adapted to engage the opposite sides of crotch 10 and hold the frame from collapsing and at the same time maintain it in 75 position for supporting the barrel at the desired angle, the angle being more or less acute determined by the adjustment, as will be understood. The outer extremity of bar 11 may be provided with the looped handle 13 for conveniently manipulating the same, 80 and this handle may be pivoted thereto at 12' in order to turn down out of the way, pivot 12' being available as a crotch-engaging stop in manner similar to pins 12.

The straight upper extremities 2' of cradle-forming arms 2 are longitudinally slotted at 14 and formed with ratchet teeth notches 14', and adapted to embrace the upper half of the barrel by curved strap 15. Projecting from opposite sides of the strap 95 are pins 16 which are movable in slots 14 and have ratchet-like coaction with notches 14'. Strap 15 is formed with a biting edge 15' which impinges the top surface of the barrel as shown in Fig. 2. The strap may 100 be conveniently manipulated by the extremity handles 17. With the parts thus arranged, any movement of the supported barrel in the direction of end b' exerts such pressure on strap 15 as to cause pins 16 to 105 lower in slots 14 of arms 2, and with the hold of pins maintained by ratchet notches 14' the barrel is securely held against dis-

placing movement, and is maintained at the desired angle, determined by the adjustment of bar 11, for dispensing its contents.

The construction of the improved support 5 is such that it may be securely fastened to the barrel when the latter is resting on its side as shown in full lines in Fig. 1. After being thus applied the support is adapted to coöperate with the barrel in so manipulating the same as to up-end the barrel into the dotted position of Fig. 1, the lower extremity 4' of the appropriate leg 4 serving as a turning point for the combined rolling and tipping movement which carries the 10 barrel from the full line to the dotted line position shown. And with the barrel thus inclined and resting on the chine of end b, and with both of legs 4 resting on the floor, only slight effort is required to turn and tip the 15 support and barrel into the full upright position of Fig. 2. For these manipulations leg extremities 4' provide a non-slipping hold on the floor. When fully upright, the support is wholly sustained by casters 5 and 20 9, so that in effect the support comprises a truck for moving the barrel from place to place.

When not in service bar 11 is sprung 25 downwardly from its engagement with crotch 10, and the parts are adapted to fold together with arms 2 and legs 4 substantially parallel with bar 6, and strap 15 turned down onto arms 2.

I claim:—

35 1. A barrel jack comprising a frame having a pair of supporting legs extending toward one end of the supported barrel and other floor-engaging supporting means extending toward the opposite end of the barrel, means for securing the frame to a barrel when the latter is resting on its side and with one of the legs of said pair adapted to engage the floor and coöperate with the 40 barrel chine for turning the barrel into inclined upright position with said pair of legs resting on the floor and coöoperating with the barrel chine in supporting the barrel in inclined position, said pair of legs 45 constituting a fulcrum upon which the frame is adapted to be turned into full upright barrel-supporting position.

2. A barrel jack comprising a frame having upwardly extending cradle-forming arms and a pair of depending legs rigid 50 with said arms, other floor-engaging means secured to the cradle-forming arms and adapted to coöperate with said legs in forming a support for sustaining a barrel with its axis substantially horizontal, the frame 55 having a support adapted to engage one end of the barrel, and means for holding the barrel against longitudinal movement in the cradle-forming arms.

3. A barrel jack comprising a frame having upwardly extending cradle-forming

arms and a pair of depending legs rigid with said arms, other floor-engaging means secured to the cradle-forming arms and adapted to coöperate with said legs in forming a support for sustaining a barrel with 70 its axis substantially horizontal, a device extending from the cradle-forming arms to one end of the barrel and adapted to engage the latter for holding the barrel against longitudinal movement in one direction, and 75 means for securing the cradle-forming arms to the barrel for holding the latter against longitudinal movement in the opposite direction.

4. A barrel jack comprising a frame having upwardly extending cradle-forming arms and a pair of depending legs rigid with said arms, other floor-engaging means secured to the cradle-forming arms and adapted to coöperate with said legs in forming a support for sustaining a barrel with 80 its axis substantially horizontal, a device extending from the cradle-forming arms and adapted to engage one end of the barrel, and a band extending across the upper portion 85 of the barrel with the opposite ends of the band adjustably secured to the cradle-forming arms.

5. A barrel jack comprising a frame having upwardly extending cradle-forming 90 arms and a pair of depending legs rigid with said arms, other floor-engaging means secured to the cradle-forming arms and adapted to coöperate with said legs in forming a support for sustaining a barrel with 95 its axis substantially horizontal, a support extending from the cradle-forming arms and adapted to engage one end of the barrel, a barrel embracing band, and means securing the opposite ends of said band to the opposite 100 cradle-forming arms with said means operating to increase the hold of the band on the barrel upon movement of the barrel in direction away from its end support.

6. A barrel jack comprising a frame having upwardly extending cradle-forming 105 arms adapted to embrace a barrel midway its ends, a pair of divergent legs depending from and rigid with the cradle-forming arms, a device pivotally secured between its 110 ends to said cradle-forming arms and leg structure with one end of said device comprising an arm which extends to and is adapted to engage one end of the barrel, the opposite portion of said pivoted device deflected downwardly and comprising floor-engaging means, and means for rigidly uniting the pivotally connected frame parts.

7. A barrel jack comprising a frame having divergent upwardly extending barrel-embracing arms, a pair of divergent downwardly extending legs rigid with said arms, said arms and legs, respectively, diverging in direction transversely of the barrel axis, a device extending longitudinally of the bar- 125 130

rel axis and between its ends pivotally connected to the said rigidly united arms and legs, one end of said pivoted device extending to and adapted to engage an end of the barrel, the opposite portion of the pivoted device bifurcated and disposed downwardly to form a pair of supporting legs, and adjustable means for rigidly connecting the said pairs of legs for maintaining the latter 10 in upright uncollapsed position.

8. A barrel jack comprising a frame having divergent upwardly extending barrel-embracing arms, a pair of divergent downwardly extending legs rigid with said arms, 15 said arms and legs, respectively, diverging in direction transversely of the barrel axis, a device extending longitudinally of the barrel axis and between its ends pivotally

connected to the said rigidly united arms and legs, one end of said pivoted device extending to and adapted to engage an end of the barrel, the opposite portion of the pivoted device bifurcated and disposed downwardly to form a pair of supporting legs, and a bar secured to the first named pair 25 of divergent legs and extending between the last named pair of legs with means for securing the bar to said last named legs and thereby rigidly holding the frame in uncollapsed position. 30

In testimony whereof I affix my signature in presence of two witnesses.

ROBERT M. KINNARD.
